WELDED PLOW FROG

Rudolph J. Altgelt, South Bend, Ind., assignor to
 Dearborn Motors Corporation, Highland Park,
 Mich., a corporation of Delaware

Application January 12, 1950, Serial No. 138,211

1 Claim. (Cl. 97—113)

1

This invention relates to an improved welded plow frog for moldboard plows.

Moldboard plows generally utilize a moldboard having a compound curved surface and the share used in conjunction with a moldboard is also arcuately formed to blend with the curvature of the moldboard. As is well known, the share and the forward edge of the moldboard receives the most wear during the operation of the plow because such portions of the plow penetrate the soil first and receive the brunt of the erosion and wear. As the share element of the plow is relatively inexpensive such share can be cheaply replaced with a new one when worn, however, the moldboard of the plow is comparatively difficult to manufacture and is correspondingly more expensive than the share hence its replacement is an item of considerable moment. In order to reduce the wear on the moldboard it has been customary to shorten the moldboard somewhat by reducing the overall length of the moldboard and providing a replaceable shin piece ahead of the moldboard and in abutment with the moldboard proper. The shin piece being a much smaller member is more readily manufactured and hence can be cheaply replaced by a new one when worn. The moldboard proper which receives relatively little wear can then remain on the plow for an indefinite period.

To adequately support the various elements of the moldboard plow, an angularly shaped frog or standard is generally provided. Such frog or standard is, however, a highly complicated member to fabricate from a single plate of steel due to the compound curve required on the moldboard face of the frog in order to receive the correspondingly curved moldboard, and the angular relationship of the landside and moldboard faces of the frog. Such a frog requires expensive dies for its fabrication. Another disadvantage of the conventional frog is the lack of an adequate mounting for the shin piece which makes it exceedingly difficult to properly secure the shin piece to the plow.

Accordingly, it is an object of this invention to provide an improved built-up frog construction of easily shaped members which may be joined by welding to provide a sturdy unitary frog.

Another object of this invention is to provide an improved frog for a moldboard plow having an improved mounting for the shin piece of the moldboard.

The specific nature of this invention, as well as other objects and advantages thereof, will become apparent to those skilled in the art from

2

the following detailed description, taken in conjunction with the attached sheet of drawings on which, by way of preferred example only is illustrated one embodiment of this invention.

5 On the drawings:

Figure 1 is a side elevational view of the landside face of a moldboard plow incorporating the improved frog of this invention.

10 Figure 2 is a plan view of Figure 1.

Figure 3 is a fragmentary cross sectional view taken along the plane 3—3 of Figure 1.

Figure 4 is an enlarged fragmentary cross sectional view taken along the plane 4—4 of Figure 2.

15 Figure 5 is a perspective view of the improved frog of this invention.

As shown on the drawings:

In Figure 1 there is shown a plow bottom 10 comprising essentially a frog 11, a moldboard 12 mounted on the moldboard face of frog 11 and a landside 13 mounted on the landside face of frog 11. The improved frog 11 of this invention, best shown in Figure 5, comprises a landside plate member 14, and a moldboard plate member 15. The plate members 14 and 15 are blanked out in suitable dies and then pressed to the shape shown in the appended drawings. Plate 14 is essentially a flat plate of somewhat triangular configuration. Plate 15, however, while of the same general shape as plate 14, is provided with an arcuate surface 15a having a curvature corresponding to the curved working surface of moldboard 12. An integral upstanding ear member 15b having a transverse hole 15d is provided on the upper forward corner of plate 15 for a purpose to be later described. Ear 15b is disposed above the landside face 14 of frog 11 and projects outwardly and laterally beyond the face of such member. The forward edge of plate member 14 is bevelled as shown at 14a and the forward edge of plate member 15 abuts the bevelled edge 14a so that plate members 14 and 15 abut in angular relationship and such plate members are welded in this position, as indicated at 11a, to provide a unitary frog. The forward edge 15c of plate member 15 which projects beyond plate 14 is bevelled to provide a flush joint on the forward edge of frog 11, as best shown in Figure 5.

Frog 11 is the main support of the various elements of the plow. Moldboard 12 is mounted on the plate member 15 of frog 11 spaced somewhat above the bottom of such frog and rearwardly of the forward edge as shown in Figure 2, such moldboard being secured to plate member 15 by three spaced bolts 12a. A share 16 is

mounted on the lower edge of plate member 15 of frog 11 in abutting relation with moldboard 12 and is secured to such plate member by bolts 16a. A shin piece 17 comprising essentially a triangular member having an arcuate surface conforming to the arcuate surface of moldboard 12, is mounted on plate 15 of frog 11 ahead of moldboard 12 and in abutment therewith as shown in Figure 2. A bolt 17a secures the lower portion of shin 17 to frog 11 and a bolt 17b provided near the upper end of shin piece 17 passes through hole 15d in ear 15b thereby securing the upper end of shin piece 17 to frog 11. Hole 15d is so located in ear 15b that bolt 17b will be disposed above and laterally of landside face 14 of frog 11 as best shown in Figure 4. From an inspection of the drawings it is readily apparent that without the provision of ear 15b it would be a difficult problem to adequately secure shin piece 17 to plate member 15 because there would be insufficient bearing surface to support the shin piece and not sufficient section to permit the boring of a transverse hole for the receipt of a bolt.

The landside 13 is secured to the landside plate 14 of frog 11 in a horizontal position as shown in Figure 1 by bolts 13b. The forward end 13c of landside 13 is arcuately shaped to snugly abut the rear curved surface of share 16. Plow bottom 10 is mounted on the lower end portion of a plow beam 18, such plow beam projecting downwardly and in contact with the inside face of plate member 14 of frog 11 as shown in Figure 1. Two bolts 18a passing through transverse holes 14c provided in plate member 14 as shown in Figure 5 and through suitable holes in beam 18, secure the beam to frog 11. A third bolt 18b passes through a transverse hole (not shown) in landside 13 and through a hole 14d in frog 11 to secure the rear end of beam 18 to frog 11.

From the above description it will be apparent that the improved frog of this invention is readily fabricated by the use of relatively inexpensive dies and forming processes. The extremely heavy and expensive equipment formerly required to shape a frog from a single sheet of metal is eliminated by the improved construction of the frog of this invention hence resulting in a less expensive unit to fabricate. Joining the forward edges of the two plate members of the frog by welding provides a unitary construction which is at least equal to the conventional construction in strength and utility and the integral ear formed on the moldboard receiving plate of the frog provides a convenient and inexpen-

sive means for readily attaching the shin piece to the frog.

It will, of course, be understood that various details of construction may be varied through a wide range without departing from the principles of this invention and it is, therefore, not the purpose to limit the patent granted hereon otherwise than necessitated by the scope of the appended claim.

10 I claim:

A plow construction comprising a built-up frog including a pair of angularly disposed plate-like members, one of said members being arcuate in configuration and the other of said members being planar in configuration, said other member having an arcuate leading edge snugly abutting the rear face of said one member and rigidly welded thereto along the entire arcuate line of contact therebetween to define a sharp leading frog edge, a moldboard terminating at its front edge in spaced relation to said frog leading edge and having a rear face in flatwise contact with the exterior face of said one member, a landside in flatwise contact with said other of said members adjacent the lower edge thereof and having an arcuate forward edge lying in the plane of the rear face of said moldboard and in contact with the leading edge of said one member, a shin having a rear edge abutting the front edge of said moldboard and a leading edge overlying said landside in contact with the upper portion of the landside forward edge and projecting vertically thereabove, said first frog member having an integral upstanding projection extending laterally past the frog leading edge to directly overlie the landside, said projection and said shin having aligned bolt holes therein also overlying said landside, a bolt extending through said bolt holes to secure said shin directly adjacent the leading edge thereof to said frog projection, and other bolt means securing said moldboard and said landside to said frog.
